UNITED STATES PATENT OFFICE.

JOHN A. BROBERG, OF LINCOLN, KANSAS.

COMBINATION HAMES AND COLLAR.

1,128,404.

Specification of Letters Patent. Patented Feb. 16, 1915.

Application filed July 28, 1914. Serial No. 853,679.

To all whom it may concern:

Be it known that I, JOHN A. BROBERG, citizen of the United States, residing at Lincoln, in the county of Lincoln and State of 5 Kansas, have invented certain new and useful Improvements in Combination Hames and Collars, of which the following is a specification.

This invention relates to improvements in 10 hames of harnesses and arranged to serve likewise as a horse collar, or combining a horse collar with hames, and has for one of its objects to increase the efficiency and utility of devices of this character.

15 Another object of the invention is to provide a device which may be adapted to hames of different sizes without material structural change in the form or outline of the same.

20 With these and other objects in view the invention consists in certain novel features of construction as hereinafter shown and described and then specifically pointed out in the claims; and in the drawings illustrative 25 of the preferred embodiment of the invention, Figure 1 is an elevation from the bearing side of a pair of hames with a collar attachment applied thereto, the collar attachment being in section on one of the 30 hames. Fig. 2 is a transverse section on the line 2—2 of Fig. 1. Fig. 3 is a sectional detail view illustrating a modification in the construction.

In the improved device the hames are 35 precisely alike except that they are rights and lefts, and they are constructed in the usual outline or form and may be of metal or wood, or a combination of wood or metal as may be preferred, and it is not desired 40 therefore, to limit the invention in any manner in this respect, but for the purpose of illustration, the improved device is shown arranged in Figs. 1 and 2 applied to a conventional wood hame, while in Fig. 3 the 45 invention is shown applied to a conventional metal hame.

The body of the hame, as indicated conventionally at 10, is of the usual outline and provided with strap receiving recesses 11 at 50 the outer end and provided with metal binding straps 12 of the usual form which extend over the recesses and form closures to their outer sides. At their lower ends, the body portions 10 of the hames are curved 55 inwardly and reinforced by metal plates 13. The means for fastening the hames together

is not shown, as it forms no part of the invention and any of the various fastening or coupling devices may be employed. The bearing face, or the face which is disposed 60 next to the horse, is usually rounded and bears within the hame groove of the horse collar, but in the improved device, the bearing face of the hame is hollowed out for a major portion of its length, as indicated at 65 14, the hollowed portion forming a relatively long longitudinal recess which comes opposite the shoulders of the horse when the hames are applied. The portions of the body 10 at the sides of the hollow or depression 14 thus form ribs which operate as stops to protect the filling material, as hereafter explained. Each hame is provided with a flexible covering, indicated at 15, of leather, rubber, or like material, and completely incloses the recess 14 and extends beyond the same at the ends, as shown. The space between the body 10 and the covering and including the recess or depression is 70 filled with a suitable yieldable packing material such as hay, hair, or the like, or the material which is usually employed for the filling of horse collars. The recesses 14 are relatively deep and the outer curvature of the covering 15 is relatively large, so that a 75 80 relatively large amount of the filling material, indicated at 16 may be employed, as shown in Figs. 2 and 3 thus materially increasing the cushioning effect and producing the same result as with the ordinary 85 horse collar. The portions of the body 10 at the sides of the depression 14 assist in holding the covering 15 spaced away from the bottom of the depression, and thus 90 likewise protect the filling 16 and prevent 95 it from being crushed by any abnormal pressure to which the device may be subjected. The widest and largest portion of the recess 14 and the packing 16 is located 100 opposite the shoulder bones of the animal, thus protecting the animal from undue pressure or the formation of sores or abrasions 105 from unequal or abnormal strain or friction.

By employing the simple device illustrated, the ordinary horse collar and pad 110 are dispensed with, as the improved device combines all the advantages and utility of the ordinary horse collar, pad and hames.

The improved device is simple in construction, can be easily and inexpensively 115 manufactured without decreasing the strength or weight of the hames, and with-

out materially increasing the expense over the ordinary hames.

Having thus described the invention, what is claimed as new is:—

- 5 1. A combined horse collar and hames including a body having a depression extending longitudinally thereof with supporting ribs at the sides of the depression, a flexible covering connected to the body and bearing over the ribs and the depression, and yielding material within the body depression and between the covering and the body.
- 10 2. A combined horse collar and hames including a body having a depression extend-
- 15

ing longitudinally thereof intermediate the ends with supporting ribs at the sides of the depression, a flexible covering connected to the body and bearing over the ribs and the depression and extending above and below the terminals of the depression and in contact with the body, and yieldable filling material within the body depression and between the covering and the body. 20

In testimony whereof I affix my signature 25 in presence of two witnesses.

JOHN A. BROBERG. [L.S.]
